VENETIAN BLIND

George F. Brent and James M. Guthrie, Pittsburgh, Pa.; said Guthrie assignor to said Brent

Application September 18, 1935, Serial No. 41,157

12 Claims. (Cl. 156—17)

The invention relates to Venetian blinds, and consists in refinements and simplifications in the construction of such blinds.

A Venetian blind includes in structure a vertically extending series of opaque slats which are suspended upon two or more flexible straps. The slats of the group are angularly adjustable; they may be adjusted in unison to lie in spaced-apart horizontal planes, and, alternately, they may be tilted in such manner that the successive slats overlap and provide a closed screen. Between these two extreme positions of angular adjustment, the slats may be tilted to any desired degree, whereby the light-admitting spaces between the opaque slats may be regulated as desired. Additionally, the horizontal slats are movable relatively to one another, thereby admitting adjustment of the vertical extent of the blind, and permitting, when desired, the entire group of slats to be gathered or nested at the top of the window or other opening in which the blind is installed.

More particularly the invention pertains to improved and simplified means for effecting the above-mentioned adjustments of the slats of a Venetian blind. The invention further embraces certain refinements in structural detail, as will appear in the ensuing specification.

In the accompanying drawings Fig. I is a view in front elevation of a window casement, showing a Venetian blind embodying the invention installed therein; Fig. II is a fragmentary view, illustrating in cross section (on the plane II—II, Fig. I), and to larger scale, the organization of the slats with their supporting straps; Fig. III is a fragmentary, sectional view of the structure, taken on the plane III—III, Fig. I, and shown on larger scale than Fig. I but on smaller than Fig. II; Figs. IV and V are fragmentary views on the scale of Fig. III, illustrating partly in section and partly in elevation (on the planes IV—IV and V—V, respectively, of Fig. III) the side channels of the blind structure; Fig. VI is a fragmentary, sectional view of the installation, taken on the plane VI—VI of Fig. I, and to larger scale; Fig. VII is a fragmentary view to still larger scale, showing the basal slat and several intermediate slats of the blind in elevated positions; Fig. VII shows the structure, partly in front elevation and partly in section, on the plane indicated at VII—VII in Fig. VI; Fig. VIII is a fragmentary view comparable with Fig. VII, but showing only the basal slat, and illustrating a modification in detail; Figs. IX and X are sectional views, taken on the planes IX—IX and X—X of Fig. VIII, re-

spectively; Fig. XI is a fragmentary view comparable with Fig. VIII, and illustrating still another modification; and Fig. XII is a view in perspective of a particular sliding element embodied in the structure of Fig. XI.

In the drawings the reference numeral 1 is applied to a window frame or casement in which a Venetian blind embodying the invention is installed. The blind consists of a head-bar 2, a basal bar or slat 4, and an intervening series of opaque slats 6. In usual way, two or more vertical hangers 3 are suspended from the head-bar 2, and are secured at their lower ends to the basal bar 4. As shown in Fig. II, each hanger 3 includes a pair of flexible straps 3a and 3b, between which paired cross-bands 5, 5 extend, at uniformly spaced-apart points vertically of the straps. The straps are flexible, and, conveniently, are formed of fabric tape, to which the cross-bands 5, 5 (also formed of fabric) are united, by stitching or interweaving in manner well-known to the art. The slats 6 lie between the paired cross-bands 5, 5, and are thereby supported in vertically spaced relation, as illustrated in Fig. I.

Adjacent each of the opposite sides of the window casement 1, a vertical way 7 is provided; the opposite ways 7 extend in common vertical plane, and the opposite ends of head-bar 2 and slats 6 extend into such ways, as shown in Fig. III. In this case channels 8a and 8b of thin sheet metal provide the ways, and the channels are secured to the opposite sides of the window casement 1, say by means of nails or screws 9. The head-bar 2 is pivotally supported at its opposite ends, whereby it may be turned upon a horizontal axis. In normal position the head-bar lies in a horizontal plane, and the several slats 6 and basal bar 4 severally lie in planes spaced therefrom and parallel thereto. When the head-bar is axially turned, the outer straps 3a of the two hangers move upward and the inner straps 3b move downward (or vice versa, depending upon the direction of turning of the head-bar). Accordingly, all of the slat-supporting cross-bands 5, 5 moved into inclined positions, and the slats 6 and basal bar 4 are tilted in unison and to equal degree. In this way the light-admitting spaces between the slats may be regulated.

Advantageously, the pivotal mounting for the head-bar 2 is incorporated in the channels 8a and 8b, and, advantageously, the means for tilting the head-bar are organized with one of such channels. More specifically, an embossment 10 is formed near the top of each channel mem-

ber 8a, 8b; the embossments may be semispherical and may be pressed from the bodies of the channels, say by means of metal-shaping dies; each embossment 10 includes an orifice 10a, to receive a pin 11 extending axially from the end of head-bar 2 (Fig. III), and one of the embossments 10 (cf. Fig. IV) is slotted outward from its pin-receiving orifice 10a, whereby the head-bar 2 may be readily mounted and dismantled, 5 in the well-known manner in which the ordinary window-shade roller is installed and removed from its supporting brackets. It will be understood, therefore, that the entire slat assembly is tiltably supported by the head-bar 2, with the opposite ends of the slats laterally confined within the channels 8a and 8b. The means for tilting the assembly consists in a flexible wire or cable 12 secured at its opposite ends, by means of eye-screws 13, Figs. III and VI, to the opposite corners 10 of the head-bar 2 that lie within the channel 8a. From the two eye-screws 13 the wire 12 extends downward, within the side flanges of channel 8a, in two vertical reaches, and, adjacent the foot of the channel, the wire passes beneath two 15 pulleys 40, rotatably mounted on the channel 8a, in the relative positions shown in Fig. VI. As shown in Figs. I and VI, one of the side flanges of channel 8a is provided with an elongate, vertical slot 14; through such slot a slide 15 projects, and is made fast with the wire 12, note 20 Fig. VI; the slide 15 is secured in slot 14, and includes a knob or finger-grip 15a, by means of which the slide may be moved longitudinally of the slot. It will be perceived that, by moving 25 the slide upward in the slot 14, the wire 12 will effect the clockwise turning (Fig. VI) of the head-bar 2; or, by moving the slide downward, the head-bar will be turned counter-clockwise. By virtue of such structure the head-bar may be 30 readily turned in either direction about its axis, and, in consequence, the slats of the blind in known manner may be adjusted in the desired tilted position.

In the case of smaller installations—installations of the sizes normally used in the home—it has been found that the usual mechanism for raising and lowering the blind may, with attending advantages, be eliminated. In lieu of such mechanism, supporting means or detents are 45 organized with the opposite ends of the basal bar 4, to the end that the basal bar may be raised and lowered by hand, and will remain in adjusted position. As shown in Figs. IV to VII, such means are found in a hookless fastener—a so-called zipper. That is to say, a pair of fabric strips 16, 16, provided in known manner along their meeting edges with interlocking elements 17, is secured vertically upon the inner face of each channel 8a, 8b. A slide 18 (Fig. VII) of usual 50 sort is organized with each pair of strips 16, 16, and in known way the slide may be moved upward and downward over, and in engagement with, the elements 17 carried by the companion edges of such strips, thereby alternately interlocking and releasing said elements. The invention is concerned with the locking and interlocking of the fastener elements 17 only insofar as force must be applied to the slide 18 to effect the operation. That is, the slide 18 tends to 55 remain in any position into which it is slid longitudinally (i. e., vertically in this case) of the companion fastener strips 16, 16, and requires a positive application of force to move it.

In the manner indicated in Fig. VII, each end of the basal bar 4 is pivotally or rockably secured to

the slide 18 of the hookless fastener 16, 16 secured to the channel (8a or 8b) into which such end of the bar extends. An eye-screw 19 is secured in the center of each end of the basal bar, and engages the link 20 which is provided in usual way upon the slide 18. Thus, the two ends of the basal bar are secured to slides 18, and, by manually moving the basal bar 4 vertically upward or downward, the two slides 18 move in corresponding direction along their associated strips 10 16, 16. The slides 18, by virtue of their inherent tendency to resist movement longitudinally of the fastener strips, sustain the basal bar in adjusted position.

In the case of larger and heavier structures, 15 the slides 18 will be equipped with a locking device, positively to secure them in desired position. Such locking slides may be found in slide fasteners on the market today, and illustration of them is deemed unnecessary.

In the above described manner, the basal bar 4 may be adjusted vertically. As the basal bar is elevated, the flexible hangers 3 progressively fold, as indicated at 30 in Fig. VII, and the slats 6 gather or nest successively, one upon another; 25 and, manifestly, the effective vertical extent of the blind structure within the window may be regulated as desired. It will be understood that the play in connections (19, 20) that secure the basal bar 4 to the slides 18 permit such axial 30 turning or rocking of the basal bar as is incident to the tilting adjustment of the slat assembly.

In Figs VIII to X, inclusive, a modification in the means for guiding and securing the basal bar 4 is illustrated. A vertical guiding rail 21 is embodied in each channel 8a, 8b, and such rail may be integrally formed in the body of each channel, as shown in Fig. X. A slide member 22 of general U-shape (Fig. X) is positioned upon 40 the rail, and the slide member embodies a leaf-spring 23 that bears against one side of the rail and frictionally secures the slide member thereon. A rigid pin 24 projects from the slide member, and a socket 25, conveniently formed in a 45 screw 52 (Fig. VIII) and embodied in the end portion of basal bar 4, receives such pin. In this manner each of the opposite ends of the basal bar 4 is pivotally connected to a slide member 22, and, as the basal bar is vertically adjusted, the 50 members 22 slide upon the vertical guiding rails 21. When bar-adjusting pressure is relieved, the frictional engagement of the slide members upon the rails serves to secure the parts in adjusted positions. And, manifestly, the pin-and-socket 55 engagement of the basal bar with the slides admits of the desired axial turning or rocking of the bar during the tilting adjustment of the slats as above-mentioned.

In further refinement, the faces of the guiding rails 21 may be undulated or serrated, as shown at 21a in Fig. XI, and each slide member 22a may carry a detent 22b, adapted yieldingly to engage the serrations, and afford a more secure (yet slideable) engagement of the slide member 65 with the rail.

Returning to Fig. VI, it will be understood without illustration that in modification of the wire 12 the slat-tilting means may consist in a rigid or semirigid rod or bar extending upward 70 from the slide 15 to one corner of the head-bar 2. The rod may be pivotally connected to the slat in such manner that vertical movement of the slide 15 will effect the turning of the head-bar.

It will be perceived in Fig. I that the Venetian 75

blind of this invention is exceedingly neat in appearance; the cumbersome head structure found at the top of the usual Venetian blind has been eliminated; no unsightly hardware fixtures are open to view; the usual adjusting cords, that hitherto have spoiled the artistic symmetry of Venetian blinds, have been dispensed with, and the simplified adjusting mechanisms of this invention are hidden within the channels 8a and 8b. 5 The blind is economical to construct, and may be installed readily and quickly. It will be further observed that, by virtue of the above-described structure, the slats 6 need not be perforated in the usual way for the use of guiding cords. The 10 channels 8a, 8b serve laterally to hold the slats 6 in vertical alignment, and the channels also afford means for guiding the slats during the vertical adjustment of the blind. The art will appreciate the value of a Venetian blind structure 15 in which every slat is positively guided and retained without recourse to perforating the slats, without providing them in some specialized shape, and without providing the slats with some auxiliary guiding fixtures. 20

25 In service the slats 6 become soiled, and from time to time must be removed and cleaned. To admit of the ready removing of the slats, one or both sides of the guiding ways 7 (Fig. III) are removable. Advantageously, the side flange 8d of the channel 8b may be moved into such position that the left-hand ends of the slats 6 beneath head-bar 2 may be swung out from the channel 8b, whereby, without dismantling the structure, the slats may be severally withdrawn from between said head-bar and said basal bar, the slats may be severally withdrawn from between the supporting bands 5, 5 of the flexible hangers 3. Indeed, it is easy to lift the head-bar 2 from its supports 10, and to remove the entire slat assembly from the window. In this case the side flange 8d is hinged to the base of channel 10 8b, and may be swung from its normal position to the dotted line position 8d', indicated in Fig. III, to admit of slat removal. And one or more thumb screws 26 (Figs. I and IV) cooperate with lugs 27, outstanding from the base of channel 5 8b, to secure the side flange 8d in its normal, slat-guiding position, the position indicated in full lines in Fig. III.

We claim as our invention:

1. In a Venetian blind including a vertical series of horizontally extending slats and means for tiltably supporting the slats, the combination of two vertical, horizontally spaced-apart ways into which said slats at their opposite ends extend, and means organized in one of said ways for tilting the slats. 15

2. In a Venetian blind including a vertical series of horizontally extending slats and means for tiltably supporting the slats, the combination of two vertical, horizontally spaced-apart channels, means extending vertically of one of said channels for tilting said slats, and means accessible externally of such channel for operating said slat-tilting means.

3. In a Venetian blind including a vertical series of horizontally extending slats and means for tiltably supporting the slats, the combination of two vertical, horizontally spaced-apart channels, means extending vertically of one of said channels for tilting said slats, and means slidable relatively to such channel for operating said slat-tilting means.

4. In a Venetian blind including a vertical series of horizontally extending slats and means for tiltably supporting the slats, the combination of two vertical, horizontally spaced-apart channels, means extending vertically of one of said channels

for tilting said slats, and means guided for movement vertically of such channel and accessible externally thereof for operating said slat-tilting means.

5. In a Venetian blind including a vertical series of horizontally extending slats and means for tiltably supporting the slats, the combination of two vertical, horizontally spaced-apart channels, means extending vertically of one of said channels for tilting said slats, a slot in such channel, and means movable longitudinally of said slot for operating said slat-tilting means.

6. In a Venetian blind including a vertical series of horizontally extending slats and means including flexible hangers for vertically supporting the slats, the combination of two vertical channels into which the slats at their opposite ends extend, said channels providing means for maintaining the vertically supported slats in lateral alignment, and at least one of said channels including a movable side portion, whereby slats may be readily removed from the assembly.

7. In a Venetian blind including a head-bar, a basal bar, and a vertical series of horizontally extending slats supported on flexible hangers between said head-bar and said basal bar, the combination of a slat-supporting vertically guided detent adjacent each of the opposite ends of said basal bar, and means for rockably connecting the detents to the basal bar for common vertical movement while admitting of angular movement of the basal bar.

8. In a Venetian blind including a head-bar, a basal bar, and a vertical series of horizontally extending slats supported on flexible hangers between said head-bar and said basal bar, the combination of a vertically extending way at each of the opposite sides of said slat assembly, means extending vertically in each of said ways, and a slat-supporting detent connected to each of the opposite ends of said basal bar, said detents severally cooperating with said means, and providing vertically adjustable support for said basal bar.

9. In a Venetian blind including a head-bar, a basal bar, and a vertical series of horizontally extending slats supported on flexible hangers between said head-bar and said basal bar, the combination of a vertically extending channel at each of the opposite sides of said slat assembly, into which channels said slats at their opposite ends extend, rails carried by said channels and extending vertically, and a slat-supporting detent connected to each of the opposite ends of said basal bar, said detents severally engaging said vertically extending rails and providing vertically adjustable support for said basal bar.

10. In a Venetian blind including a head-bar, a basal bar, and a vertical series of horizontally extending slats supported on flexible hangers between said head-bar and said basal bar, the combination of a vertically extending way at each of the opposite sides of said slat assembly, into which ways said slats at their opposite ends extend, means extending vertically in each of said ways, and a slat-supporting detent connected to each of the opposite ends of said basal bar, said detents severally engaging said vertically extending means and providing vertically adjustable support for said basal bar, and means organized in one of said ways and cooperating with said head-bar for adjusting the angular position of said vertical series of slats.

11. In a Venetian blind including a head-bar, a basal bar, and a vertical series of horizontally

extending slats supported on flexible hangers between said head-bar and said basal bar, the combination of a channel supported in vertical position at each of the opposite sides of said slat assembly, means organized with one of said channels for angularly adjusting the series of slats, means in said channels for vertically supporting said basal bar, said means being rockably connected to the opposite ends of said basal bar to admit of angular movement of the basal bar for the purpose described.

12. A Venetian blind including a head-bar, a basal bar, and a vertical series of horizontally

extending slats supported on flexible hangers between said head-bar and said basal bar, a channel vertically positioned at each of the opposite sides of said slat assembly, means included in said channels (and substantially hidden from view) for tilting the slats of said assembly, and means rockably connected to the opposite ends of said basal bar for supporting such bar in various positions of vertical adjustment while admitting of said angular adjustment of the slat assembly. 10
